CLAIM

The ornamental design for a jewelry chain, as shown and described.

DESCRIPTION

FIG. 1 is a top plan view of a sectional length of jewelry chain according to the invention, shown in a non-fastened, non-use position, the bottom plan view being a mirror image;

FIG. 2 is a side edge elevation view thereof from one side, the opposite side edge view being a mirror image; and, FIG. 3 is an end edge elevation view thereof, the view from the opposite end being a mirror image.
